UNITED STATES PATENT OFFICE

90,936

DESIGN FOR A DRAPERY FABRIC OR THE LIKE

Clarence P. Baxter, Ridgewood, N. J.

Application August 31, 1933. Serial No. 49,174

Term of patent 3½ years

To all whom it may concern:

Be it known that I, CLARENCE P. BAXTER, a citizen of the United States, residing at Ridgewood, Bergen County, State of New Jersey, have invented a new, original, and ornamental Design for a Drapery Fabric or the like, of which the following is a specification, reference being had to the accompanying drawing, forming a part thereof.

Figure 1 is a front view of the drapery fabric showing my novel design.

Figure 2 is a view showing the reverse side of the drapery fabric shown in Figure 1.

The warp threads A consist of relatively fine, lustrous threads, whereas weft threads B consist of dull, relatively coarse, single strands of yarn giving the design a ribbed effect. Contrasting fillet threads C are displayed between the ribs formed by the weft threads, accentuating the grooves.

I claim:

The ornamental design for a drapery fabric or the like as shown and described.

CLARENCE P. BAXTER.
